UNITED STATES PATENT OFFICE.

JOHN B. SWAN, OF GLADSTONE, MICHIGAN.

SANDING DEVICE FOR LOCOMOTIVES.

1,276,824.

Specification of Letters Patent. Patented Aug. 27, 1918.

Application filed January 12, 1917. Serial No. 141,971.

To all whom it may concern:

Be it known that I, JOHN B. SWAN, a citizen of the United States, residing at Gladstone, in the county of Delta and State of Michigan, have invented a certain new and useful Improvement in Sanding Devices for Locomotives, of which the following is a full, clear, concise, and exact description, reference being had to the accompanying drawings, forming a part of this specification.

My invention relates to sanding devices for locomotives and is concerned with improved means for protecting and directing the sand flow.

The sanding of railroad rails from the locomotive has presented quite a problem because of the fact that the end of the sand pipe or nozzle is necessarily exposed to the weather. The sand pipe or nozzle is frequently choked and sometimes entirely clogged in cold weather by the "freezing of the sand" more accurately the freezing of the moisture in the sand, causing it to pack solid and clog itself, and the freezing of condensed moisture from the rails and other sources, such as the steam from the locomotive, rain and snow upon the end of the sand pipe or nozzle with the formation of ice as an obstacle to the flow of the sand.

Devices have been provided in the prior art with the intention of eliminating these difficulties but another difficulty has arisen from the fact that the protecting means often interfered with the most efficient directing of the sand flow.

My invention provides an improved device which more effectively takes care of the protection of the sand pipe or nozzle and which also provides more effectively for the direction of the flow than has heretofore been possible.

According to my invention I provide an arrangement wherein the point of feed of the sand is protected against the elements, wherein the sand pipe end or nozzle is protected as a whole against cold by static air pockets, and which is of simplified construction.

I shall now proceed to a detailed description of the preferred form of my invention and shall refer to the accompanying drawing, in which—

Figure 1 is an elevational view of the

sanding device of my invention disposed in proximity to the rail and wheel;

Fig. 2 is an axial sectional view; and

Fig. 3 is an axial sectional view at right angles to the plane of Fig. 2.

The device as a whole is in large part preferably integral and the structure is such as to make a simple casting, of iron for instance, possible. The device provides the actual feeding nozzle which forms an extension for the sand pipe itself. The feeding nozzle is shown at 1 and, as illustrated, is surrounded by two complete flaring skirts 2 and 3, all three elements extending from a head 4 which is provided with a screw threaded socket adapted to receive the threaded end of the sand pipe 6, a set screw 7 being provided to hold the parts thus joined firmly together.

It will be seen that the inner skirt 2 is longer than the nozzle 1 and that the outer skirt 3 is still longer, each element having an oblique end and the outer member particularly having its end so formed as to permit of close proximity to the rail and wheel, the top of the rail being indicated by the line 8 and the wheel being shown at 9.

The nozzle 1 is of practically uniform formation but the skirts, as stated, flare, and, as shown, flare gradually at first and then more strikingly outward. The flare is greater on its vertical axial plane than on its transverse axial plane and the oblique ends of the three elements permit ready flow of the sand toward the wheel after it leaves the nozzle and at the same time protects the flow from the wind from the front. The direction of travel is indicated by the arrow X.

It will be seen that there are thus two complete static air pockets surrounding the nozzle, thus effectively insulating the nozzle 1 against the cold. The end of the nozzle 1, the point of feed, lies protected first by the longer inner skirt and then by the still longer outer skirt. Any formation of ice on the outer skirt, where moisture accumulates would have to bridge the gap to the inner skirt and then the gap to the nozzle before it could affect the sand flow from the nozzle, and that is impossible. Moisture to any harmful degree will not condense primarily on the nozzle because it will strike the skirts first, with the result pointed out. Beyond

these advantages so far as protection against clogging is concerned, my structure also prevents the wind from blowing the sand out of line before it reaches the rail, the greater flare of the skirts lying in the vertical cross section, so as to provide a maximum distance from the nozzle end and especially protecting the downward flow of the sand onto the rail, as will be evident from Fig. 1.

10. The transverse cross section flares less as shown to confine the flow against side thrust away from the rail as much as possible.

As a matter of simple and economical structure the skirt 2 is integral with the head 4, the outer skirt 3 extending from and being integral with the inner skirt, while the sand pipe end or nozzle 1 is screwed into the head. It will also be noted that the nozzle 1 is flattened at its lower end to accord it to the respective vertical and transverse flares of the skirts.

I claim:

1. In a sanding device, a sand pipe, and a skirt surrounding said sand pipe and flaring outwardly therefrom, the point of feed being isolated from the edge of said skirt, said skirt flaring more in the downward vertical plane than in the other planes, and the end of said sand pipe being flattened to accord thereto, said skirt insulating said sand pipe from moisture and cold.

2. In a sanding device, a sand pipe, a skirt surrounding said sand pipe and flaring outwardly therefrom and extending below the lower end of the sand pipe, the lower end of the sand pipe being the point of feed and a second skirt surrounding said first named skirt flaring therefrom and extending below the same.

40. 3. In a sanding device, a sand pipe, a skirt surrounding said sand pipe and flaring outwardly therefrom and extending below the lower end of the sand pipe, the lower end of the sand pipe being the point of feed and a second skirt surrounding said first named skirt flaring therefrom and extend-

ing below the same, said skirts flaring more in vertical plane than in transverse plane.

4. In a sanding device, a sand pipe, a skirt surrounding said sand pipe and flaring outwardly therefrom and extending below the lower end of the sand pipe, the lower end of the sand pipe being the point of feed and a second skirt surrounding said first named skirt flaring therefrom and extending below the same, said skirts flaring more in the downward vertical plane than in the other planes and the end of the sand pipe being flattened to accord thereto.

5. In a sanding device, a head providing a socket adapted to thread over the end of a sand pipe, a nozzle extending from said head to form an extension from said pipe, and a skirt extending from said head and surrounding said pipe, said skirt flaring more in the downward direction than in the other directions.

6. In a sanding device, a head providing a socket adapted to thread over the end of a sand pipe, a nozzle extending from said head to form an extension from said pipe, and a skirt extending from said head and surrounding said pipe, said skirt being integral with said head, said skirt flaring more in the downward direction than in the other directions.

7. In a sanding device, a head providing a socket adapted to thread over the end of a sand pipe, a nozzle extending from said head to form an extension from said pipe, and a skirt extending from said head and surrounding said pipe, said skirt being integral with said head and a second skirt integral with said first skirt and extending from and surrounding said first skirt, said skirts flaring more in the downward direction than in the other directions.

In witness whereof, I hereunto subscribe my name this 4th day of January, A. D. 1917.

JOHN B. SWAN.
